(57) **CLAIM**

The ornamental design for an anti-pry pop-top vial, as shown and described.

DESCRIPTION

FIG. 1 is a perceptive view of the anti-pry pop-top vial in the closed position;

FIG. 2 is a perceptive view of the anti-pry pop-top vial in the open position;

FIG. 3 is a front view of the anti-pry pop-top vial in the closed position;

FIG. 4 is a front view of the anti-pry pop-top vial in the open position;

FIG. 5 is a back view of the anti-pry pop-top vial in the closed position;

FIG. 6 is a back view of the anti-pry pop-top vial in the open position;

FIG. 7 is a left view of the anti-pry pop-top vial in the closed position;

FIG. 8 is a left view of the anti-pry pop-top vial in the open position;

FIG. 9 is a right view of the anti-pry pop-top vial in the closed position;

FIG. 10 is a right view of the anti-pry pop-top vial in the open position;

FIG. 11 is a top view of the anti-pry pop-top vial in the closed position;

FIG. 12 is a top view of the anti-pry pop-top vial in the open position;

FIG. 13 is a bottom view of the anti-pry pop-top vial in the closed position; and,

FIG. 14 is a bottom view of the anti-pry pop-top vial in the open position.

The dotted lines shown in the figures represents those portions of the vial that form no part of the claimed design.
